UNITED STATES PATENT OFFICE.

ORTIZ W. MERRIAM, OF OGDEN, IOWA.

AUTOMATIC FIRE ALARM.

Application filed February 25, 1924. Serial No. 695,052.

The object of my invention is to provide an automatic fire alarm system of simple, durable and inexpensive construction which may be easily and quickly installed, and which when installed will be reliable and positive in its action, and one which needs but a minimum amount of attention to always keep it in a working condition.

My invention consists in the construction, arrangement and combination of the various parts of the device, whereby the objects contemplated are attained, as hereinafter more fully set forth, pointed out in my claim, and illustrated in the accompanying drawings, in which:

Figure 1 is a diagrammatical view illustrating my improved system.

Figure 2 is a segmental top view of one of the controlling switch devices, and also a portion of the variable resistance.

Figure 3 is an end elevation of the same.

Figure 4 is a side elevation of one of the primary switch devices.

This system is designed to operate preferably from the electric light lines of the town in which the alarm is operated.

The numeral 10 indicates the main lines of an electric lighting system. I have connected with each of the conductors of the said lines, conductors 11 and 12 and provided a third conductor which runs parallel with the right angle extending portions of said conductors 11 and 12. Connecting the conductors 12 and 13 is a series of thermostatically controlled switch devices 14. These switch devices may be placed in any position in the building in which it is desired to install the apparatus, or in such rooms as are to be protected by the fire alarm.

Each of the switches 14 comprises a frame member 15 formed substantially U-shaped and has between its parallel members a thermostatic wafer 16 of that type which will expand very readily by a change of two or three degrees in temperature. One side of the wafer 16 is secured to the leg member 17 of the frame 10, while the underside of the wafer 16 is provided with a downwardly extending pin 18 slidably mounted in the free end of the leg member 19 of the frame 15.

The leg member 19 is provided with a downwardly extending arm 20 in which is mounted a contact member 21 formed of spring material and having spaced fingers 22 so arranged that as the wafer 16 expands, the pin 18 will be moved downwardly and in

between the fingers 22, causing electric contact to be made between the members 18 and 22. The member 21 is insulated from the arm 20 and provided with a conductor 23 secured to the conductor 13, while the arm 17 is provided with a conductor 24 secured to the conductor 12.

A lamp 25 is mounted between the conductors 11 and 13 so that when either one of the switches 14 is closed, the lamp 25 will be lighted. This lamp may be placed in any prominent position, such as the outside of the building where it will attract the attention of passersby, thereby giving a signal that fire is taking place somewhere within the building. Any number of these lamps may be provided. One might be placed in the fire station also, if desired.

Between the conductors 11 and 13 and parallel with the lamp 25, I have provided what I shall term a thermo-electric switch-closing device comprising an electric heating element 26, which may consist of a plate 27 formed of insulating material over which a series of resistance wires 28 is mounted in a zig-zag manner, similar to the heating elements of electric cookers. One side of the heating element is connected to the conductor 13, while the other side is connected to a conductor 29. This conductor 29 has included a knife switch 30 and is connected with the conductor 11, thereby completing the circuit through the heating element 26 when both of the switches 24 and 30 have been closed.

A second thermostatic wafer 31 is mounted immediately above the member 26 so that it will be actuated by the heat therefrom. This wafer 31 is provided with an upwardly extending post 32 designed to carry an insulated block 33 which has two upwardly projecting pins 34, each of which is designed to make contact with a set of flexible fingers 35 so arranged that as the wafer 31 is expanded, the pins 34 will be slidably received between the said finger contacting members, thereby insuring a perfect connection.

The fingers 35 and the knife switch 30 are mounted on a suitable support 36 which is constructed of any suitable insulating material. The switch 30 comprises contact members 37 and 38, the member 38 being pivoted and free to swing in sliding contact with the member 37. The said member 37 is extended and pivotally and adjustably connected with the upper end of the rod 32, so that when the

wafer 31 has been expanded a pre-determined amount, the switch 30 may be opened and the circuit through the heater 26 disconnected. This is for the purpose of preventing the wafer expanding to such an extent that it will be in danger of bursting. As soon as the thermostat has cooled, the switch 30 will again be closed. The pins 34 are of such length that the switch 30 may be 10 opened and closed without opening the contact between the pins 34 and the fingers 35.

One of the contact members 35 is connected with a conductor 39, while the other is connected with a conductor 40. Said conductors 39 and 40 being connected with conductors 41 and 42 respectively. The said conductors form an alarm circuit in which is included an alarm device 43. The conductors 41 and 42, however, are assumed to be 15 conductors of the telephone line which leads from the central telephone office to the residence or building in which the alarm is established. The alarm circuit is completed by providing a conductor 44, one end of 20 which is connected with one of the posts 34 and leads to a variable resistance 45. One end of said resistance is connected to the conductor 13. The other post 34 is provided with a conductor 46 which is connected with 25 a variable resistance 47 similar to the resistance 45, said resistance making connection with the conductor 11.

Thus it will be seen that if one of the thermostatic switches is closed, the heating element 26 will be heated through the conductors above described, which will cause the thermostat 31 to be expanded and the post 34 to make contact with the fingers 35. This will then establish a circuit first through the 30 resistance 45, the conductor 44, the post 34 and the corresponding contact member 35, the conductor 39, the alarm 43, the conductors 42 and 40, the contact 35, the post 34, the conductor 46 and the resistance 47.

45 Inasmuch as the regular lighting system is usually of no less than one hundred ten volts, and usually an alternating current, it will be seen that the variable resistance devices 45 and 47 may be so adjusted that voltage 50 may be produced of sufficient intensity to operate the ringing mechanism of the ordinary telephone system, to thereby give an alarm to the telephone operator, or if the system is that type which employs a drop, 55 the same will be operated and the corresponding lamp 25 lighted. In the latter case the signal lamp 25 may be placed in a suitable box apart from the regular switch board, each thermostatic control system having 60 its own lamp. The name of the building

in which the system is installed is inserted opposite the lamp. The operator will then be able to ascertain where the fire is located. The telephone operator may then give alarm to the various members of the fire department. This system applies chiefly to small towns which do not have a regular fire department and depend upon volunteer service. It will be seen, however, that a bell may be 65 substituted for the regular telephone bell 70 which may be placed in the fire department headquarters if so desired, without materially changing the system.

By providing two of the variable resistances 45 and 47, each of which makes connection with the conductors of the main line, I have provided means whereby, if either of the conductors 44, 46, 39 or 40 were to become grounded, it would not be possible for 75 a sufficient current to go through the other 80 side of the system so as to burn out the telephone coils.

It will be seen that my system is so constructed that the lamp 25 and the alarm system are capable of being arranged in numerous ways which would work out most advantageously to the community in which the alarm system was installed. That is, the lamp 25 might be placed in front of the building in which the system was installed, or it might be placed in the main fire department office, or there might be a lamp both in front of the building and another one in the fire department office. Any number of lamps 85 may be used between the conductors 90 13 and 11.

It will be seen that by this arrangement I have provided an alarm system which is quite positive in its action and one in which the upkeep is reduced to a minimum, and one in which the expense of installation is 100 also small, due to the fact that the wires of the system already installed are utilized to form a part of my improved system.

105 I claim as my invention:

An alarm system comprising an alternating current power circuit, an alarm circuit in parallel therewith and including an alarm device, thermostatically controlled means for closing said alarm circuit, a telephone circuit, a pair of conductors for connecting said telephone circuit in parallel with said alarm circuit, each of said conductors including a variable resistance and a switch, a thermoelectric device in said alarm circuit for closing said switches when the said alarm circuit has been closed.

110 Des Moines, Iowa, February 14, 1924.

115 ORTIZ W. MERRIAM.
